TRIPOD JACK

Roy L. Diercksmeier, Chicago, Ill., and Edward M. Pfauser, Elm Grove, Wis., assignors to Blackhawk Mfg. Co., Milwaukee, Wis., a corporation of Wisconsin

Application July 23, 1941, Serial No. 403,600

7 Claims. (Cl. 254—1)

Our invention relates generally to improvements in the art of elevating, propping and lowering diverse objects such as airplanes; and relates more specifically to various improvements in the construction and operation of tripod jacks of the portable type and which are adjustable to meet various conditions of use.

A general object of our invention is to provide a new and useful tripod prop and jack assemblage which is simple and durable in construction, and which is moreover highly efficient in use.

It has heretofore been proposed as shown in United States Patent No. 2,227,460, granted January 7, 1941, to Otto Morgensen, Jr., to provide a portable airplane jack having a tripod, an upright object-engaging member slidably centrally of the tripod, and mechanical advantage means such as a hydraulic jack or ram for moving the work engaging member; and while this prior patented airplane jack is quite satisfactory and effective for most of its intended uses, it is relatively cumbersome and complicated, and is not adapted to meet all conditions of use which arise when lifting, propping and lowering planes. A jack and prop structure of this kind must be compact but powerful, quickly manipulable and reliable in action, and readily transportable and conveniently applicable to the plane elements in crowded and restricted quarters. Such an assemblage should also be sufficiently stable to resist tilting or other displacement when in use, and the lifting power should preferably be applied to the work as directly as possible; and provision should also be made for effecting rapid and universal adjustment of the object engaging plunger relative to the work and for placing and locking the plunger prop in any position of vertical adjustment. While the previously patented jack assemblage does meet many of the specific requirements, it fails to meet all of them in a satisfactory manner, and although the prior structure makes provision for elevating bodies distances greater than the length of the stroke of the hydraulic jack and for locking the work engaging prop in some positions of vertical adjustment, this locking can only be effected at fixed intervals and is not universal throughout the entire range of adjustment.

It is therefore a more specific object of our present invention to provide an improved jack and prop for airplanes or the like, which most effectively meets all of the above mentioned conditions and requirements, and which is extremely flexible in its adaptations and uses.

Another specific object of the present invention is to provide a sturdy and extremely simple tripod jack assemblage having enormous power considering the total space occupied, and which can be readily bodily transferred from place to place and utilized in cramped localities.

A further specific object of this invention is to provide an improved prop having mechanical advantage means for varying the effective length thereof, and in which the work engaging member may be quickly and effectively placed and locked in any desired position of adjustment.

Still another specific object of the invention is to provide a simple and strong framework for a tripod or the like, the fixed height and spread of which can be conveniently altered, and which can be readily assembled or dismantled for compact storage.

An additional specific object of our invention is to provide an improved hydraulic jack assembly which is especially adapted for use as a mechanical advantage means in conjunction with an airplane tripod or prop.

Another specific object of this invention is to provide various improvements in the details of construction of hydraulically actuated tripod jack assemblages of the portable type, whereby the cost of construction of such devices is reduced to a minimum, while the efficiency thereof is enhanced to a maximum.

These and other specific objects and advantages of the invention will be apparent from the following detailed description.

A clear conception of the several features constituting the present improvement, and of the manner of constructing and of manipulating portable hydraulic tripod jacks embodying the invention, may be had by referring to the drawings accompanying and forming a part of this specification wherein like reference characters designate the same or similar parts in the various views.

Fig. 1 is a front elevation of one of the improved hydraulic tripod jack assemblages of minimum height, showing the work-engaging plunger in lowermost position, and also having a portion of the supporting legs on one side broken away;

Fig. 2 is a similar elevation of one of the improved assemblages drawn to reduced scale and having a tripod of somewhat greater initial height;

Fig. 3 is another similar elevation of one of the improved assemblages likewise drawn to reduced

scale and having a tripod structure of still greater initial height;

Fig. 4 is a greatly enlarged central vertical section through the improved hydraulic jack or ram, with the plunger in lowermost position and the work-engaging member lowered, the medial portion of the ram having been broken away;

Fig. 5 is a side elevation of one of the upper leg attachments and of one of the jack carrying handles;

Fig. 6 is a side elevation of fragments of the ram plunger and upper adjusting ring, showing the locking pin coacting with these elements;

Fig. 7 is a sectional view similar to the upper portion of Fig. 4, but showing the ram plunger elevated and locked against retraction relative to the ram cylinder and tripod;

Fig. 8 is a bottom view of the ram cylinder showing the mode of attachment of the three centering braces; and

Fig. 9 is a section through one of the tripod supporting feet.

While our invention has been shown and described herein by way of illustration, as being embodied in three legged hydraulic tripod jack assemblages of the portable type especially adapted for airplane services, it is not our desire or intent to thereby unnecessarily restrict the scope or utility of the improvement, and the term "tripod" is intended to apply to prop assemblages having any number of supporting legs.

Referring to the drawings, the improved airplane jack shown therein comprises in general, a tripod consisting of an upper hub 10 provided with a central vertical partially threaded bore 11 and having sets of integral radiating ears 12 to which supporting legs 13, 13', 13'' are removably and pivotally attached by means of transverse bolts or pins 14; a mechanical advantage device or hydraulic ram consisting of an elongated upright cylinder 15 removably confined at its upper end within the hub bore 11 by set screws 16 coacting with a groove, and having its lower end sealed by a cup shaped element or head 17, and a plunger 18 coacting with and reciproccable within the bore of the cylinder 15 and being provided with an elongated plunger rod 19 slidable in an upper guiding and packing gland 20; a vertically adjustable work-engaging member or saddle 21 carried at the top of a spindle 22 having screw thread coaction with a bushing 23 which is detachably secured within the upper recessed end of the rod 19; and centering braces 24, 24', 24'' of selected lengths connected to ears on the ram cylinder head 17 by removable bolts 25, and with feet 26 secured to the lower ends of the legs 13, by means of other removable bolts 27.

The central upper hub 10 of the tripod prop is preferably formed in one-piece of durable metal, and the leg suspension pins 14 are removable from the integral ears 12 so as to permit quick detachment of the legs 13 from the hub 10. One side of the hub 10 may also be provided with a handle 28 for facilitating adjustment and transportation of the jack structure, and a locking pin 29 may also be suspended from the hub 10 by means of a chain 30 or the like. The tripod supporting legs 13, 13', 13'' may be formed of stock tubing and of any selected length in order to provide a tripod of predetermined height, as shown in Figs. 1, 2 and 3 respectively; and the upper ends of these tubular legs 13 may be provided with fittings 31 adapted to coact with the pins 14 as shown in Fig. 4, while the lower leg ends may be snugly fitted within the feet 26 and

detachably secured thereto by dowel pins 32 as illustrated in Fig. 9. The radial tripod braces 24, 24', 24'' may also be formed of selected length corresponding to the lengths selected for the legs 13, 13', 13'' respectively, as shown in Figs. 1, 2 and 3; and these braces 24 are preferably rigidly but removably attached to the cylinder head 17 and feet 26 with the aid of the pins or bolts 25, 27 respectively, so as to permit the legs 13 to be folded inwardly toward the cylinder 15 when it is desired to collapse the tripod. The hub 10, legs 13, braces 24, and feet 26 just described, constitute the tripod assembly, and as previously indicated, any desired number of legs 13 may be provided.

The improved mechanical advantage device or hydraulic ram, comprising the elongated cylinder 15, lower head 17, plunger 18, and elongated plunger rod 19, is normally fixedly mounted so that the plunger 18 and its rod 19 may be elevated by the admission of liquid under pressure to the lower displacement chamber 33 of the cylinder through a port 34, and may be lowered by gravity when the liquid pressure is relieved through this same port 34. The required liquid pressure may be derived from any desired source such as a pump mounted on one of the legs 13 and connected to the port 34 by a flexible tube or hose; and the ram piston or plunger 18 which snugly slidably engages the bore of the cylinder 15, is also provided with a cup-packing 35 near its lower end, and with an abutment 36 at its opposite end adapted to engage a similar abutment 37 at the lower end of one of the elements of the gland 20, in order to positively limit the upward stroke of the plunger 18. The elongated plunger rod 19 which is snugly but slidably confined within the upper gland 20, has its lower end either detachably secured to the plunger 18 as shown, or formed integral therewith; and the medial portion of this rod 19 is provided with a series of equally spaced parallel through holes 38 with any of which the pin 29 may be caused to cooperate to lock the plunger and rod against retraction or lowering.

In order to permit such universal locking of the plunger and rod 19 to be effected when the plunger 18 is in any position of vertical adjustment relative to the tripod, we have provided special mechanism such as shown in detail in Figs. 4, 6 and 7, at the upper extremity of the ram. Besides the vertically adjustable spindle 22 which carries the work-engaging saddle 21 and has screw thread coaction with the sleeve 23 mounted in the upper end of the rod 19, and the pin 29 coacting with the holes 38, this improved adjusting mechanism comprises a collar 39 internally screw threaded for coaction with external threads 40 at the upper extremity of the ram cylinder 15 and having a lower outer flange 41 and an upper inner flange 42; an annular stop element 43 surrounding the lower portion of the collar 39 and rigidly attached to the top of the hub 10 by cap screws 44, the element 43 having an upper inwardly directed flange 45 adapted to engage the lower collar flange 41 so as to limit the upward adjusting movement of the collar 39; and a seating ring 46 resting upon the upper collar flange 42 and detachably secured to the collar 39 by means of spring pressed pins 47, and having a series of radial recesses 48 in the upper surface thereof adapted to coact with the locking pin 29 as shown in Figs. 6 and 7.

With this improved adjusting assemblage, the externally screw threaded spindle 22 coacting with the sleeve 23 carried by the plunger rod 19,

may first be adjusted when the tripod jack has been properly positioned beneath the object which is to be raised, so as to cause the saddle member 21 to initially engage the work. The ram plunger 18 and rod 19 may thereafter be elevated by the admission of liquid under pressure to the chamber 33 so as to lift the object any desired amount within the stroke of the ram plunger 18. If this desired lift places one of the holes 38 in alignment with a diametrically opposite set of the recesses 48 in the ring 46, the locking pin 29 may be inserted in the aligned hole and recesses as shown in Fig. 7, to thereby positively retain the member 21 and the work in the desired elevated position even if the pressure in the ram displacement chamber 33 should drop. In case none of the holes 38 are disposed in alignment with a set of the recesses 48 when the desired lifting has been effected, the collar 39 may be rotated to move the seating ring 46 upwardly to an extent sufficient to cause a set of diametrically opposite recesses 48 to properly coact with the hole 38 nearest to and above the ring 46, whereupon the locking pin 29 may be inserted in order to positively prevent lowering of the work or elevated object. In this manner any desired position of vertical adjustment of the assemblage may be quickly and readily maintained without lowering the work to any extent; and in order to facilitate the adjusting operation, the exterior of the saddle member 21 and ring 46 may be knurled and the exterior of the upper portion of the collar 39 may be roughened for application of a wrench, as shown. It is also important that the lowermost hole 38 in the rod 19, be located the proper distance above the plunger 18, so that this lowest hole will be above the ring 46 when the abutments 36, 37 coact with each other, and the range of vertical adjustment of the collar 39 should also be at least equal to or slightly greater than the distance between successive holes 38.

From the foregoing detailed description, it will be apparent that our present invention provides an improved tripod jack which is extremely simple, compact and sturdy in construction, and which can be readily adjusted to elevate extremely heavy objects and locked in adjusted position. The fixed height of the improved tripod can be conveniently varied to meet different conditions of use, and the jack unit can be easily transported with the aid of the handle 22 on the hub 18 and with the aid of an additional handle 49 associated with the ram cylinder, and the assemblage can also be readily collapsed for convenient storage by merely removing either the bolts 25 or the bolts 27. The improved ram assemblage besides providing enormous power, is extremely stable and readily manipulable, and the adjusting mechanism associated with the upper hub portion of the ram permits universal positioning of the work-engaging member and locking thereof in any desired position. The tripod assemblage can be manufactured at moderate cost by virtue of the fact that the legs are formed of relatively standard stiff tubing, and this tripod assemblage besides being formed to withstand extreme stresses, can also be positioned in relatively cramped quarters without sacrificing stability.

It should be understood that it is not desired to limit this invention to the exact details of construction or to the precise mode of use, herein shown and described, for various modifications within the scope of the claims may occur to persons skilled in the art.

We claim:

1. In combination, a tripod, a hydraulic ram cylinder fixedly secured to said tripod, a plunger movable in said cylinder and having a series of holes therethrough, a work-engaging member carried by said plunger, means for effecting adjustment of said member along the axis of and relative to said plunger, a reaction element adjustable along said cylinder, and a pin cooperable with said element and with said holes to retain said plunger in any position of vertical adjustment within the limits of movement thereof.
2. In combination, a tripod, a hydraulic ram cylinder fixedly secured to said tripod, a plunger movable in said cylinder and having a series of holes therethrough, a work-engaging member carried by said plunger, means for effecting adjustment of said member along the axis of and relative to said plunger, a collar adjustable along said cylinder, a radially recessed ring associated with said collar, and a pin cooperable with the recesses of said ring and with said holes to retain said plunger in any position of vertical adjustment.
3. In combination, a tripod, a fluid pressure actuated ram having a cylinder fixedly secured to said tripod and having a plunger movable in said cylinder, said plunger being provided with a series of spaced holes extending therethrough, a work-engaging member carried by and adjustable axially along said plunger, a collar adjustable along said cylinder, a radially recessed ring carried by said collar, and a pin cooperable with the recesses of said ring and with said holes to retain said plunger in any position of vertical adjustment.
4. In combination, a tripod having a central axis, a ram having a cylinder fixedly secured to said tripod concentrically of said axis, a plunger movable along said cylinder and having a series of depressions, a work engaging member carried by said plunger, means for effecting adjustment of said member along said axis and relative to said plunger, an annular reaction element adjustable along said axis and relative to said cylinder, and a pin cooperable with said annular element and with said plunger depressions to retain said member in any position of vertical adjustment within the limits of movement of said plunger.
5. In combination, a tripod having a central axis, a ram having a cylinder fixedly secured to said tripod concentrically of said axis, a plunger movable along said cylinder and having a series of depressions, a work engaging member carried by said plunger, means for effecting adjustment of said member along said axis and relative to said plunger, an annular reaction element adjustable along said axis and relative to said cylinder, a recessed ring carried by said element, and a pin cooperable with the recesses of said ring and with said plunger depressions to retain said member in any position of vertical adjustment.
6. In combination, a tripod having a central axis, a ram having a cylinder fixedly secured to said tripod concentrically of said axis, a plunger movable along said cylinder and having a series of depressions, a work engaging member carried by said plunger, means for effecting adjustment of said member along said axis and relative to said plunger, a reaction collar adjustable along said axis and relative to said cylinder, a radially recessed ring resting upon said collar, and a pin cooperable with the radial recesses of said ring and with said plunger depressions to hold said work engaging member and said plunger in any position of vertical adjustment.

7. In combination, a tripod having a central axis, a ram having a cylinder fixedly secured to said tripod concentrically of said axis, a plunger movable along said cylinder and having a series of depressions, a work engaging member carried by said plunger, means for effecting adjustment of said member along said axis and relative to said plunger, a reaction collar screw threaded

upon said cylinder for adjustment along said axis, a recessed ring rotatably supported upon said collar, and a pin cooperable with said ring recesses and with said plunger depressions to lock the latter in various vertical positions.
